UNITED STATES PATENT OFFICE.

JERRY WILLEY, OF DES MOINES, IOWA.

SILO STRUCTURE AND ANCHORING MEANS THEREFOR.

Application filed January 2, 1923. Serial No. 610,382.

To all whom it may concern:

Be it known that I, JERRY WILLEY, a citizen of the United States, residing in Des Moines, in the county of Polk and State 5 of Iowa, have invented a certain new and useful Silo Structure and Anchoring Means Therefor, of which the following is a specification.

The object of my invention is to provide means for preventing the twisting of the staves of a silo relative to each other and to prevent up and down movement of the staves relative to each other.

More particularly, my invention relates to 15 a member arranged to extend across the joint of two adjacent staves and to be secured thereto, and fingers formed on said member arranged to form a pocket or retaining member for the wire band or hoop 20 ordinarily used on silos.

Still a further object is to provide the structure with tapered prongs whereby they may be embedded in the staves for holding 25 the plate or center member across the joint of the staves, and to form the ends of the center member with fingers arranged at right angles to the center member and projected outwardly therefrom for receiving a wire band or the like therebetween.

Still a further object is to provide a member for connecting the adjacent staves together and for retaining the silo band in such position that the band will engage, 30 through the medium of the anchoring members, each of the staves for holding them in proper position.

With these and other objects in view, my invention consists in the construction, arrangement and combination of the various 40 parts of my device, whereby the objects contemplated are attained, as hereinafter more fully set forth, pointed out in my claims, and illustrated in the accompanying drawings, in which:

Figure 1 is a side elevation of a silo with one set of anchoring members and a wire band shown thereon.

Figure 2 is a sectional view taken on line 2-2 of Figure 1.

Figure 3 is a sectional view taken on line 3-3 of Figure 2, showing the anchoring member connected to two adjacent staves; and

Figure 4 is a perspective view of one of 55 the anchoring members.

In the accompanying drawings, I have

used the reference numeral 10 to indicate generally a silo base, which has resting thereon a plurality of vertical wood staves 11 for forming a complete silo wall. A 60 roof structure 12 rests upon the staves 11.

Each of the staves 11 are provided with a groove 13 and a tongue 14 on their opposite edges. The tongue 14 of one of the staves is designed to project into the groove 65 of the next adjacent stave.

In this connection, it may be mentioned that there is some up and down movement or twisting movement of the staves relative to each other, which causes the entire silo wall 70 to sag and twist.

My anchoring members are designed to eliminate the possibility of up and down movement of the staves relative to each other and to eliminate sagging of the silo wall. 75

My anchoring members are formed of a single piece of material A. The material A is provided with a center member 15 which has a pair of prongs 16 on each of its ends. The prongs 16 are tapered and are 80 bent at right angles to the center member 15.

The prongs 16 are capable of being driven into the wooden staves 11 for holding the anchoring member in position. The prongs 85 16 are so embedded in the staves 11 that the center member 15 will extend across the joint between a pair of adjacent staves, as clearly shown in Figures 1 and 3 of the drawing.

From the construction of the parts just described, it will be seen that the anchoring members are secured to the staves and will prevent up and down movement of one stave relative to another and thus eliminate 95 any sagging of the silo wall. Each of the pieces of material A is provided with pairs of fingers 17 on the ends of the center member 15. The pairs of finger members 17 are arranged between the pairs of prongs 16 and are also bent at right angles to the center member 15. The pairs of fingers are bent in a direction opposite from the prongs 16, as clearly shown in Figure 4 of the drawing.

The adjacent edges of each pair of fingers 17 are curved so that each pair will form a half circle. The fingers 17 are designed to receive therebetween an iron silo band 18 of the ordinary construction.

It will be seen that the fingers 17 form a pocket for receiving or retaining the iron

band or hoop against up or down movement. When the iron band 18 is tightened, it will engage each of the anchoring members, as clearly shown in Figure 1 of the drawing.

5 In this connection, it may be mentioned that the providing of a plate, which extends across the joint of the adjacent staves and the resting of an iron band thereagainst is quite an advantage over the securing of an 10 iron band directly to the staves.

The using of my anchoring member makes it possible to draw all of the staves together regardless of any irregularity in the width of the staves. My anchoring members are 15 designed for use with a wood stave silo. When iron bands are used directly against the staves, I have found that it is almost impossible to get the iron band to rest on each of the edges of the staves.

20 My device causes the staves to be connected securely together with their edges resting against each other. The iron band 18 rests directly against the center member 15, which in turn is fixed to the adjacent 25 staves, thereby completely anchoring the staves against undesired movement.

Some changes may be made in the construction and arrangement of the various parts of my invention, without departing 30 from the real spirit and purpose of my invention and it is my intention to cover by my claims, any modified forms of structure or use of mechanical equivalents, which may be reasonably included within their scope.

35 I claim as my invention:

1. In combination with a silo having a plurality of vertical staves arranged with coacting tongues and grooves on their adjacent edges, an anchoring means for preventing twisting movement of staves relative to each other, said anchoring means comprising a member adapted to extend over the joint of two adjacent staves, tapered prongs on said member adapted to extend 40 into said staves and spaced fingers projected from the ends of said member in a direction

opposite from said prongs for receiving an iron band therebetween for forming a pocket therefor.

2. An anchoring member for wood silo staves for preventing their up and down movement and for holding an iron band in position comprising a center member, tapered prongs formed on the ends of said center member, said prongs being bent at 55 right angles to said center member and adapted to be embedded in the wooden staves, fingers on the ends of said center member and bent at right angles thereto in a direction opposite from the prongs for forming a receiving pocket for an iron band.

3. An anchoring member for wood silo staves for preventing their up and down movement and for holding an iron band in position comprising a center member, 60 tapered prongs formed on the ends of said center member, said prongs being bent at right angles to said center member and adapted to be embedded in the wooden staves, a pair of fingers on each end of said 65 center member, said pairs of fingers being bent at right angles to said center member, the adjacent edges of said pairs of fingers being curved so that each pair forms substantially a half circle receiving pocket as 70 and for the purposes stated.

4. In combination with a silo wall composed of wood staves having coacting tongues and grooves, means for preventing up and down movement of the staves relative to each other and for retaining an iron band in position, comprising a center member, means for fastening said center member to two adjacent staves, a pair of fingers on each end of said center member, said pairs of fingers being bent at right angles to said center member, the adjacent edges of said pairs of fingers being curved so that each pair forms substantially a half circle receiving pocket as and for the purposes stated.

Des Moines, Iowa, December 21, 1922.
JERRY WILLEY.
